SHOE-HEEL CONSTRUCTION

Erasmo Pipitone, Hoboken, N. J.

Application June 3, 1944, Serial No. 538,631

4 Claims. (Cl. 36—34)

My invention relates to a heeled shoe. Ordinarily, the heel is affixed to the remaining or main body of the shoe by nails. This structure has several drawbacks. It cannot withstand considerable stress, the nails holding the heel by mere frictional engagement, and consequently the heel may become loose or even may be lost. The nailing damages the pierced material. The upper ends of the nails often press through the superposed layers, may damage a lining, an insole or an interposed cushion and may even hurt the foot and the stockings. In addition the nailing makes the repair or replacement of the heel difficult.

Objects of my invention are to avoid all these drawbacks and to secure the heel to the shoe body without nails, to provide a structure which withstands considerable stress, and to provide a heel which securely supports the main shoe body.

Other objects are to make the mounting, dismounting and replacement of the heel easy, quick and efficient.

A further object is to provide a resiliently cushioned shoe in which the cushion can not come in contact with nails.

Still further objects and advantages will appear from the following description of an exemplifying embodiment of my invention and of a modification thereof, from the appended claims and from the accompanying drawings in which:

Fig. 1 shows a partially sectional side elevation of a shoe representing an illustrative embodiment of the invention.

Fig. 2 shows a part used in the embodiment shown in Fig. 1, said part being seen in original condition from the upper side in Fig. 1.

Fig. 3 shows the part shown in Fig. 2, seen from the left side in Fig. 2.

Fig. 4 shows another part of the same embodiment seen from the lower side in Fig. 1.

Fig. 5 shows the heel of the same embodiment, seen from the lower side in Fig. 1.

Fig. 6 shows another modification of the part shown in Fig. 4 in the same position as Fig. 4.

Fig. 7 shows a side elevation of the part shown in Fig. 6 in a position corresponding to Fig. 1.

Fig. 8 shows the part shown in Figs. 6 and 7 seen from the right side in Fig. 7.

Referring to the embodiment of my invention shown in Figs. 1 to 5, numeral 1 indicates a platform, preferably of leather. A metal shank 2, preferably of thin steel, is superposed on the platform 1 and may be pressed into the upper surface thereof. A small bridge or angularly bent strip of metal 3 is permanently affixed to the lower

side of 2, for example, by welding or soldering. The platform 1 has a perforation or window where the bridge 3 is inserted. The bridge 3 has a long slot 4 with an enlarged right end 5 for the introduction of the head 6 of a screw bolt 7. This bolt is secured near the left end of the slot 4 by a square nut 8.

The heel 9 has an approximately vertical hole or bore 10 terminating at the lower side of the heel in a circular recess 11. The bolt 7 passes through the hole 10 and carries another nut 12 positioned in the recess 11. The remaining space of the recess 11 may be filled with suitable material, for example, with cement or putty, or a wood block. The screw bolt 7 may be slightly bent at a zone 13 below the nut 8, the upper end of the bolt being perpendicular to the slotted part of the bridge 3, and the lower part of the bolt projecting from the platform 1 in the direction of the hole 10. A lift or tip 17 covers the lower surface of the heel 9 and seals the recess 11.

A cushion 14 of resilient material, preferably of sponge rubber, is superposed on the shank 2 and covers also the adjacent area of the platform 1. A thin layer or insole 15, preferably of leather, covers the cushion 14 and holds the same in a slightly compressed condition with the tapered rim 16 of the cushion pressed down to the platform 1.

30 The other parts of the shoe may be made of any suitable material, and the shoe may have any shape which includes a heel.

Figs. 6 to 8 show a modification of the shank which may be used instead of that shown in Figs. 35 1 and 4. The shank 20 differs from the shank 2 in that the bridge is not separately made and thereafter affixed to the body of the shank, but is formed by a part 18 of the shank body which is pressed or stamped down. Thereby, an open recess, 19 appears over the pan-shaped part 18. The screw 7 (Fig. 1) can be inserted from the upper side, and no long slot is necessary. Instead, the bottom of the pan 18 has a circular hole 21 for the passage of the screw 7. Except for these 40 differences, the shank 20 is shaped, mounted and used in the same manner as the shank 2.

The assemblage of the shoe comprises the assemblage of the "body," that is of the shoe without heel, and the affixing of the heel and the 50 lift.

When the body is mounted, the shank is placed on the platform with the projecting bridge or pan inserted in the perforation of the platform. The screw 7 may be inserted and secured by the nut 8 before or after mounting the shank on the

platform. Then, the cushion 14 is affixed, for example, by cementing its rims to the platform. Thereafter, a lining, an insole, the "upper" and any other parts may be assembled to the platform or to the body by conventional methods.

The separately prepared heel may be finished in conventional manner. Then, the projecting end of the screw 7 is passed through the hole 10 and equipped with the nut 12. This nut is then tightened by means of a key-wrench or otherwise. Finally, the recess 11 is filled with putty or the like, and the lift 17 is fastened in conventional manner, for example, by glue or nails.

For replacement of the heel, the lift and the putty or other filler is removed and the nut 12 is unscrewed whereupon the heel can be separated from the body. Then, the body is immediately ready for mounting another heel in the manner described before.

I desire it understood that my invention is not confined to the embodiment shown and described, the same being merely illustrative, and that the invention may be carried out in other ways without departing from the spirit of the invention as it is obvious that the embodiment shown and described is only one of the many that may be employed to attain the objects of my invention.

Having described the nature of my invention, what I claim and desire to secure by Letters Patent is:

1. A shoe comprising a platform having a perforation, a metallic shank superposed on said platform and having a lower projection inserted in said perforation, a heel with a hole, a bolt having one end affixed to said projection and having a part passing through said hole, and detachable means mounted on the other end of

said bolt and pressing said heel against said platform.

2. A shoe comprising a platform having a perforation, a metallic shank superposed on said platform, a slotted bridge affixed to the lower side of said shank and inserted in said perforation, a heel with a hole, a screw bolt having a head positioned below said shank over the slot of said bridge and having a shaft passing through the slot of said bridge and through the hole of said heel, a nut positioned on said bolt below the slot of said bridge and securing said bolt to said bridge, and another nut positioned on the lower end of said bolt and securing said heel to said platform.

3. A shoe comprising a platform having a perforation, a shank superposed on said platform and having a pan-shaped depression inserted in said perforation, the bottom of said depression having a hole, a heel with a hole, a screw bolt having a head positioned over said hole of said depression and having a shaft passing through said hole of said depression and through the hole in said heel, a nut positioned on said bolt below said hole of said depression and securing said bolt to said shank, and another nut positioned on the lower end of said bolt and securing said heel to said platform.

4. A shoe comprising a platform having a perforation, a shank superposed on said platform and having a lower projection inserted in said perforation, a heel with a hole, a bolt having one end affixed to said projection and having a bent shaft passing through said hole, and means mounted on the other end of said bolt and securing said heel to said platform.

ERASMO PIPITONE.
